DRAFT DIVERTER

Buckley R. Reed, Louisville, Ky., assignor to the
United States of America, as represented by the
Secretary of the Army

Application May 21, 1951, Serial No. 227,498

9 Claims. (Cl. 98—84)

(Granted under Title 35, U. S. Code (1952),
sec. 266)

1

The invention described herein, if patented, may be manufactured and used by or for the Government for governmental purposes, without the payment to me of any royalty thereon.

My invention relates to draft diverters or ventilator caps for seating atop the upper ends of vertical ventilation pipes, stove pipes, chimneys or the like to prevent downdrafts in the pipe or chimney. Specifically, the diverter according to the invention is intended to provide an improvement over the draft diverter or ventilator cap shown and described in the U. S. patent to Jack W. Kice, No. 2,470,623, dated May 17, 1949.

In devices of this type it is customary to provide two or more tubular inner diverter sections disposed in vertically or axially spaced alignment with the uppermost section closed at the upper end to provide a cap. A tubular diverter outer section usually surrounds the inner sections in outwardly spaced concentric relation thereto so as to span the space between the inner sections and overlap the adjacent ends thereof. Any number of inner and outer sections may be used but the number of outer sections will usually be one less than the number of inner sections for obvious reasons. The inner and outer sections, arranged as aforesaid, are connected together by means providing spacers and it is with such spacers that the invention is particularly concerned.

With the foregoing in view, it is an object of the invention to provide in combination with a draft diverter, an improved spacer for the several diverter sections.

A further object is to provide an improved spacer for a number of draft diverter sections, which spacer includes means for anchoring a guy wire to the diverter.

A further object is to provide an improved spacer for draft diverter sections which is operative to strengthen the assembled diverter in use, improve the operation thereof, and one which is readily made by normal manufacturing methods and which is capable of being incorporated with standard diverter sections to provide the diverter.

A further object is to provide a novel and improved draft diverter incorporating the above described spacers.

Other objects and advantages reside in the particular structure of the invention, the structure of the several elements thereof, combinations and sub-combinations of such elements, all of which will be readily understood by those skilled in the art upon reference to the attached drawing in connection with the following specification,

2

wherein the invention is shown, described and claimed.

In the drawing:

Figure 1 is an elevation of a draft diverter according to the invention;

Figure 2 is a longitudinal, vertical sectional view taken substantially on the plane of the line 2—2 of Figure 1;

Figure 3 is a horizontal sectional view taken substantially on the plane of the line 3—3 of Figure 1, parts being omitted for clarity, and

Figure 4 is a perspective view of a spacer according to the invention apart from the rest of the structure.

Referring specifically to the drawing, wherein like reference characters have been used throughout the several views to designate like parts, 10 designates the upper end of a chimney, smoke stack, stove pipe, exhaust pipe or the like while 11 designates generally a diverter according to the invention.

In the embodiment illustrated, the diverter 11 comprises three tubular inner diverter sections 12, 13 and 14 disposed in vertically spaced and aligned relation. The uppermost section 14 is provided with an end wall or closure 15 whereby this section provides a cap to restrict the entrance of rain or snow into the pipe 10. The lowermost section 12 is shaped and sized for a sliding fit with the free end of the pipe 10 and may be provided with a suitable means such as the inwardly directed annular bead 16 for limiting the telescoping of the pipe 10 therein by providing a fixed stop for the free edge of such pipe.

The inner sections 12, 13 and 14 are surrounded by two tubular diverter outer sections 17 and 18 which are likewise in spaced vertical alignment but which are vertically staggered with respect to the inner sections so that they span the spaces between such inner sections and overlap the adjacent ends thereof. As is readily apparent, this arrangement prevents or at least restricts direct downdrafts in the stack or pipe 10 caused by winds or drafts. The inner and outer diverter sections are retained in the spaced relation aforesaid by means now to be described.

Such means comprises a plurality of substantially identical spacers 20 best seen in Figure 4. The spacers 20 are disposed between the inner and outer sections and extend longitudinally of the assembled sections in substantially equally spaced relation to each other. In the embodiment illustrated, there are three spacers used but it is obvious that any number necessary may be utilized.

The preferred form of spacer illustrated by way of an example comprises an inner flange 21 and an outer flange 22 which are connected together in substantially parallel relation by a web 23. The arrangement of flanges and web is substantially Z-shaped but obviously could be I-shaped, C-shaped or possibly of other shape within the scope of the invention as hereinafter claimed.

As best seen in Figure 3, the spacers 20 have the outer peripheries of the outer flanges 22 fixedly connected to the inner peripheries of the outer sections 11 and 18 in any suitable manner as by being welded thereto. Likewise, the inner peripheries of the inner flanges 21 are similarly connected to the outer peripheries of the inner sections 12, 13 and 14 so that the webs 23 extend substantially radially of the assembled inner and outer sections whereby to provide substantially rigid spacing means for maintaining the spaced concentric relation of the inner and outer sections. Of course, the outer and inner flanges 22 and 21 respectively maintain the vertically spaced relation of the outer and inner sections. In addition to the aforesaid strengthening provided by the webs 23, the webs also provide baffles tending to break up eddy currents between the inner and outer diverter sections which otherwise would adversely affect the draft in pipe 10. Preferably, the outer flanges 22 of the spacers are not longer than the overall length of the two outer sections and the lengths of the webs 23 may be similarly restricted. However, the lengths of the inner flanges 21 are necessarily greater to provide upper and lower end portions extending above and below the outer sections for connection respectively with the upper inner section 14 and the lower inner section 12.

The lower ends of the inner flanges 21 are doubled on themselves as at 24 and formed to provide bights 25 in which are seated guy anchors 26 of any suitable form, such anchors being swingably or hingedly seated in such bights. The doubled end portions 24 are preferably secured together to close the bights 25. Any suitable means may be utilized for this purpose but in the preferred form, such means comprise rivets 27 which pass through aligned holes 28 in the doubled end portions 24. As shown, the rivets 27 also pass through the lowermost inner sections 12 to secure the doubled end portions to the such section. This arrangement supplements the previously described welded connection of the parts to provide additional strength to compensate for the additional strains imposed by guys, not shown, secured to the guy anchors 26.

In the form of diverter illustrated, there are three inner diverter sections and two outer diverter sections. Obviously, the number of sections may vary with the needs of the situation. Thus, there may be as few as two inner sections with but a single outer section therebetween, or there may be any desired larger number of inner and outer diverter sections.

It is apparent from the foregoing that the inner and outer sections are substantially plain sections of tubular stock with the exception of the uppermost inner section 14 which requires the end wall 15. Moreover, it is apparent that no modification of the inner and outer sections is required to connect them together by the spacers 20 of the invention. Finally, it is apparent that no additional modification of the sections is necessary to provide guy anchors for the pipe 10, and that the particular spacers serve not only to increase the

strength of the assembled diverter sections but also serve to increase the efficiency of the diverter as a whole by breaking up eddy currents between the inner and outer diverter sections.

Moreover, while I have shown and described what is now thought to be the preferred embodiment of the invention, it is obvious that the same is susceptible of other forms and expressions. Consequently, I do not limit myself to the precise structures shown and described hereinabove except as hereinafter claimed.

I claim:

1. In a draft diverter for seating atop a chimney, the combination with three tubular diverter inner sections arranged in axially spaced and aligned relation, the uppermost inner section having a closed upper end providing a cap, and two axially spaced and aligned tubular diverter outer sections surrounding said inner sections in outwardly spaced concentric relation so as to span the spaces between said inner sections and overlap the adjacent ends thereof; of a plurality of spacers for connecting all of said sections together in said spaced relation aforesaid, said spacers being substantially identical and being substantially Z-shaped in end elevation to provide inner and outer flanges connected by a web, said outer flanges each having a length not greater than that of the combined length of said outer sections and being fixed to the inner peripheries thereof, said inner flanges being substantially longer than said outer flanges and having upper and lower ends extending above and below said outer sections, portions of each inner flange being fixed to the outer peripheries of all of said inner sections, said lower ends of said inner flanges being doubled upon themselves to provide bights, and looped guy anchors swingably seated in said bights.

2. A draft diverter according to claim 1, and wherein means are provided for securing said doubled lower ends of said inner flanges together to close said bights and retain said anchors therein.

3. A draft diverter according to claim 2, wherein in said last-named means is operative to secure said doubled lower ends of said inner flanges to the lowermost of said diverter inner sections.

4. A draft diverter according to claim 3, wherein in said webs of said spacers have lengths corresponding to those of said outer flanges.

5. In a draft diverter for seating atop a chimney, the combination with at least two tubular diverter inner sections arranged in axially spaced and aligned relation, the uppermost inner section having a closed upper end providing a cap, and at least one tubular diverter outer section surrounding said inner sections in outwardly spaced concentric relation so as to span the space between said inner sections and overlap the adjacent ends thereof; of a plurality of spacers for connecting all of said sections together in said spaced relation aforesaid, said spacers being substantially identical, each spacer including aligned upper and lower ends and a radially outwardly offset central portion, each central portion being not longer than the length of said outer section and being secured to the inner periphery thereof, said upper and lower ends of said spacers being secured to the outer peripheries of said inner sections, said lower ends of said spacers being doubled on themselves to provide bights, and guy anchors seated in said bights.

6. A draft diverter according to claim 5, where-

in means are provided for securing said doubled lower ends of said spacers together to close said bights and retain said guy anchors therein.

7. A draft diverter according to claim 6, and wherein said last-named means is also secured to the lowermost of said diverter inner sections.

8. In a draft diverter for seating atop a chimney, the combination with at least two tubular diverter inner sections arranged in axially spaced and aligned relation, the uppermost inner section having a closed upper end providing a cap, and at least one tubular diverter outer section surrounding said inner sections in outwardly spaced concentric relation so as to span the space between said inner sections and overlap the adjacent ends thereof; of a plurality of spacers for connecting all of said sections together in said spaced relation aforesaid, said spacers being substantially identical and comprising inner and outer flanges connected by a web, said outer flanges each having a length not greater than that of said outer section and being fixed to the inner periphery thereof, said inner flanges being substantially longer than said outer flanges and having upper and lower ends extending above and below said outer section, portions of each inner flange being fixed to the outer peripheries of both inner sections, said lower ends of said inner flanges being doubled on themselves to provide bights, guy anchors seated in said bights, and means securing said doubled lower ends of said inner flanges together and to the lowermost of said diverter inner sections to close said bights and retain said anchors therein.

9. In a draft diverter for seating atop a chimney, the combination with at least two tubular

diverter inner sections arranged in axially spaced and aligned relation, the uppermost inner section having a closed upper end providing a cap, and at least one tubular diverter outer section surrounding said inner sections in outwardly spaced concentric relation so as to span the space separating said inner sections and overlap the adjacent ends thereof; of a plurality of spacers for connecting all of said sections together in said spaced relation, said spacers each comprising an inner and an outer flange connected by a web, said outer flanges each having a length not greater than that of said outer section and being fixed to the inner periphery thereof, said inner flanges being longer than said outer flanges and having lower ends extending below said outer section, portions of each inner flange being fixed to the outer peripheries of both inner sections, guy anchors for said diverter, and said lower ends of said inner flanges being formed to provide means for attaching said guy anchors thereto.
